CLAIM

We claim the ornamental design for a spout for packaging container, as shown and described.

DESCRIPTION

FIG. 1 is a top perspective view of a spout for packaging container, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 bottom perspective view thereof;

FIG. 9 is a cross-sectional view taken along line 9-9 in FIG. 6; and,

FIG. 10 is a reference view thereof shown with a packaging container.

The broken lines in FIGS. 1-5 and 8 show portions of the spout for packaging container which form no part of the claimed design. The broken lines in FIG. 10 show environmental structure which form no part of the claimed design.

1 Claim, 8 Drawing Sheets
